UNITED STATES PATENT OFFICE.

BENJAMIN G. RAND, OF NORTH TONAWANDA, NEW YORK.

FILING CABINET.

Application filed March 19, 1924. Serial No. 700,250.

This invention relates to an index file or cabinet for signature cards, account cards, and other index matter.

Its chief object is to provide a simple and efficient cabinet of this character constructed of a plurality of independent units or sections which may be added to from time to time to suit the needs of the user.

Another object of the invention is to provide novel means for effectually interlocking the sections of the cabinet against displacement relative to one another.

A still further object is to provide a cabinet of this kind which enables the trays or panels containing the index matter to be withdrawn from the cabinet to assume an inclined or pendent position convenient for inspection or posting and in which the connections between the trays and their companion supporting sections are such as to permit the complete detachment or removal of the trays, when desired.

In the accompanying drawings:

Figure 1 is a perspective view of the improved cabinet, showing one of the trays or panels withdrawn and supported therefrom in a pendent position. Figure 2 is a central longitudinal section thereof, on an enlarged scale. Figure 3 is a cross section on line 3—3, Fig. 2. Figure 4 is an enlarged longitudinal section of one of the cabinet sections and its tray, the latter being shown in a pendent position. Figure 5 is a perspective view of the top section of the cabinet, the cover plate being partially broken away. Figure 6 is a similar view of one of the intermediate tray sections. Figure 7 is a similar view of the bottom section. Figure 8 is a perspective view of one of the detachable locking devices or springs.

Similar characters of reference indicate corresponding parts throughout the several views.

In its general organization, this improved filing cabinet comprises a plurality of independent separable units or sections of uniform size and shape disposed in a vertical series one above the other, and detachable means for locking each unit to an adjoining unit, whereby the several units making up the cabinet are rigidly and securely held against accidental displacement in all directions.

In the preferred embodiment of the invention shown in the drawings, the same comprises a lower or bottom section 10, an upper

or top section 11, and a series of intermediate sections 12 having trays or drawers 13 for containing records or other matter to be filed. In the drawings, four of such tray sections are shown, but it will be understood that any number of these sections may be employed, depending on the capacity desired by the user for any one cabinet. The several sections may be rectangular in shape and constructed of furniture steel or other appropriate material.

The bottom section 10 of the cabinet is of substantially inverted box-like form, its depending side and end walls terminating in inwardly and upwardly-bent marginal rims or flanges 14 which not only make for a rigid structure but also form a channel 15. For the purpose of reinforcing the top wall of this section, Z-shaped braces 16 may be used which rest at their lower ends upon the edges of the flanges 14 while their upper ends may be welded or otherwise fastened to the underside of said top wall, as shown in Figs. 2 and 3.

The top section 11 is of substantially box-like form, its upwardly extending side and end walls terminating in inwardly and downwardly-bent marginal rims or flanges 17 forming a channel 18 similar to the channel 15 of the bottom section. The open upper side of this top section may be closed by a removable cover-plate 19 which snugly fits in place without the use of fastenings, the same resting on ledges 20 secured to the side walls of said section. As shown in Fig. 2, these ledges are spaced from the end walls of the section, so that by simply depressing on either end of the cover plate, its opposite end is raised clear of the upper end of the section, as shown by dotted lines in Fig. 2, whereby it can be conveniently grasped for removal, when desired.

The intermediate or tray-sections 12, which are arranged between the top and bottom sections, are identical in construction, each consisting of a box-like frame structure closed on all sides except the top and front sides, the front side being open to permit of the insertion and withdrawal of the respective tray 13 containing the index matter. The top of each tray-section is left open for the purpose of applying and removing the locking devices employed for detachably connecting the several sections together, as will hereinafter appear. The longitudinal side walls of each tray-section are provided

at their upper ends with inwardly and downwardly-bent flanges 21 which form corresponding channels 22. The trays rest on the bottom walls of their companion sections and their side walls engage the opposing upright portions of the flanges 21, whereby the trays are guided in their movement lengthwise of said sections. The rear walls of the latter form stops for the trays, insuring a uniform closing of all of them. The front wall of each tray preferably extends upwardly in close proximity to the underside of the adjacent unit-section of the cabinet to render the same substantially dust-proof, as well as to afford a maximum protection in case of fire.

The preferred means for separably connecting the several sections 10, 11 and 12 into a completely assembled cabinet consist of detachable spring locking devices 23 which are constructed to securely fasten one section to an adjoining section and which are arranged in sets, one set serving to unite two of the cabinet sections against both lateral and vertical displacement relative to one another. To this end, each locking device is in the form of a spring wire or rod having an eye or handle 24 at one end and an offset or angularly disposed interlocking projection 25 at its other end, said projection including substantially horizontal bearing portions 26 and a vertical web portion 27 connecting them, as shown in Fig. 8. These locking rods are disposed lengthwise on opposite sides of the cabinet and occupy the spaces created by the flanges 14, 17 and 21 of the cabinet-sections 10, 11 and 12, respectively, one end of each rod bearing against the horizontal portion of the corresponding flange while the other end is adapted to interlock with the contiguous portions of adjoining sections. For this purpose, the top wall of the bottom section 10 is provided adjacent its side walls and near the end walls thereof with vertical openings 28, while the bottom of the top section 11 and the bottoms of the intermediate sections 12 are provided with similar alining openings 29 and 30, respectively. The horizontal portions of the flanges 21 formed on the intermediate tray-sections are also provided with openings 31, all of the openings in the several sections being in vertical alinement in the assembled position thereof. The offset projection of each locking rod is adapted to interlock with the registering openings of adjoining sections, its web 27 engaging directly with such openings and its horizontal portions 26 bearing against the adjacent portions of said sections on opposite sides of their openings, as shown in Fig. 2. After engaging the rod with a pair of openings, its eye-end 24 is forced downwardly below the edge of the respective flange 14, 17 or 21, and then allowed to spring, under its

own tension, into the corresponding channel formed by such flange, the vertical wall of the latter preventing lateral displacement of the rod inwardly of the cabinet. The combined locking and gripping action afforded by the several rods acts to firmly and tightly draw the cabinet sections together into a rigid structure. During the act of assembling or dismembering the tray-sections, their trays 13 must first be removed in order to permit the ready insertion and removal of the locking rods 23.

In the drawings, two locking rods are shown in opposed relation for securing each side of adjoining sections together, but it is to be understood that any number of them may be employed, if desired. It will be noted also, as shown in Fig. 2, that the lowermost tray-section 12 is fastened to the bottom section 10 by the rods carried by the latter, and that each of the remaining tray-sections and top section 11 also contain locking rods, thus requiring one set less of these rods than there are sections to a given sized cabinet.

If desired, the handles 24 of the locking-rods contained within the top section of the cabinet may be bent inwardly beyond the marginal flanges 17 to facilitate their application and removal.

Each tray 13 is preferably provided in its front wall with a finger-hole 32 to permit its ready withdrawal. By this construction, there are no projections at the front side of the cabinet liable to interfere with the inclined or pendent position which the trays are permitted to assume upon being withdrawn.

In adding tray-sections from time to time to suit the needs of the user, it is only necessary to remove the top section, apply the additional tray sections in the manner heretofore described and then replace said top section.

To enable each tray to assume an inclined position with its front edge resting on the table or other support on which the cabinet is placed, or to assume the pendent position shown by full lines in Figs. 1 and 2, it is preferably provided at its rear end with a downwardly and forwardly-bent U-shaped lip or flange 33 extending transversely thereof which is adapted to engage a corresponding rearwardly-bent inclined lip or flange 34 formed at the front end of the tray-section, as shown clearly in Fig. 4. Said lips constitute a hinge connection between these parts when they encounter each other, permitting a vertically-swinging movement of the tray on the lip 34 as a fulcrum. During this swinging movement of the tray, the top edge of the cabinet-flange 34 contacts with the inner curved face of the companion tray-flange 33. Furthermore, when it is desired to entirely detach or remove a tray

from the cabinet to carry the same about for various purposes, it is only necessary to withdraw such tray, allow it to swing to the pendent position shown in Figs. 1 and 5 2, and then lift it in a substantially vertical line, which movement will cause the tray-flange 33 to become disconnected from the flange 34 of the tray-section. Obviously, the 10 insertion of each tray in the cabinet is accomplished by a reversal of these operations.

This improved sectional cabinet is manifestly simple in construction, its sections are capable of ready assemblage and dismemberment by the user, and the same can 15 be manufactured at a moderate cost.

I claim as my invention:

1. A filing cabinet of the character described, comprising a plurality of separable sections arranged in a vertical row, the side 20 walls of the sections having inturned flanges, and detachable locking devices disposed lengthwise of the sections and occupying the spaces formed between the side walls thereof and their flanges, one end of each of said 25 devices interlocking with the contiguous portions of adjoining sections, while the other end thereof engages under the flange of one of the sections.

2. A filing cabinet of the character described, comprising a plurality of separable sections arranged in a vertical row, the contiguous faces of said sections being provided with alining openings, and spring locking devices applied to said sections, one end of 30 each of said devices interlocking with the alining openings of its companion section and an adjoining section, while its other end engages an opposing part of said companion section.

3. A filing cabinet of the character described, comprising a plurality of separable sections arranged in a vertical row, the contiguous faces of said sections being provided with alining openings, and spring locking 40 devices removably applied to said sections, one end of each locking device having an offset projection arranged to interlock with the alining openings of its companion section and an adjoining section, while its other 45 end bears against an opposing part of said companion section.

4. A filing cabinet of the character described, comprising a plurality of separable sections arranged in a vertical row, the contiguous faces of said sections being provided 50 with alining openings, and spring locking devices removably applied to said sections,

each locking device consisting of a rod having an offset projection at one end, said projection including substantially horizontal 60 portions connected by a web portion, the latter engaging the alining openings of its companion section and an adjoining section and said horizontal portions bearing against the adjacent portions of such sections, the 65 other end of said rod bearing against an opposing part of said companion section.

5. A sectional filing cabinet, comprising a base section, a top section and an intermediate tray-section, the underside of said 70 base section and the upper sides of said top and tray sections being open and provided with inturned marginal flanges, the top of said base section, the bottoms of said top and tray sections and the marginal flange 75 of said tray-section having alining openings, and spring rods for detachably locking the several sections together as a unit, said rods bearing at one end against the flanges of said base and top sections while the opposite ends 80 of said rods interlock with the openings in the contiguous portions of said last-named sections and said tray-section.

6. A sectional filing cabinet, comprising a plurality of sections arranged in a vertical 85 row and having trays slidable therein, the side walls of said sections terminating at their upper ends in inturned flanges forming longitudinal guides for the trays, and spring locking devices occupying the spaces 90 between the side walls of the sections and their trays, one end of each of said devices interlocking with the contiguous portions of adjoining sections, while the other end thereof engages under the flange of one of 95 the sections.

7. A sectional filing cabinet, comprising a plurality of sections arranged in a vertical row and having trays slidable therein, the side walls of said sections terminating at 100 their upper ends in inturned flanges forming longitudinal guides for the trays, the contiguous portions of said sections having alining openings near their front and rear ends, and oppositely-facing spring locking 105 rods applied to said sections and occupying the spaces between the side walls of the sections and their trays, one end of each locking rod having an offset projection interlocking with the alining openings of adjoining 110 sections, while the other end thereof engages under the flange of one of said sections.

BENJAMIN G. RAND.
